UNITED STATES PATENT OFFICE.

GREGORY GOULD, OF MCKINNEY, TEXAS.

DESIGN FOR AN ARTICLE OF MANUFACTURE.

356,356.

Specification for Design.

Patented Oct. 5, 1920.

Application filed February 4, 1920. Serial No. 356,241. Term of patent 14 years.

To all whom it may concern:

Be it known that I, GREGORY GOULD, a citizen of the United States of America, and resident of McKinney, in the county of Collins and State of Texas, have invented a new, original, and ornamental Design for an Article of Manufacture, of which the following is a specification, reference being had to the accompanying drawing, forming a part thereof, which shows my design as embodied in a lapel-button.

The figure is a front view of my design. The design may be applied in numerous other articles of manufacture, viz., emblems, stickpins and watch charms.

What I claim and desire to secure by Letters Patent is:

The ornamental design for an article of manufacture as shown.

GREGORY GOULD.
